The ornamental design for a solar-powered area light, as shown and described.

DESCRIPTION

FIG. 1 is a perspective view of a solar-powered area light; FIG. 2 is a top view of the solar-powered area light of FIG. 1;

FIG. 3 is a side elevational view of the solar-powered area light of FIG. 1 having a mounting flange (shown in dashed lines) mounted to an enclosed structure (also shown in dashed lines) for lighting the interior of the structure; FIG. 4 is a side elevation view of the solar-powered area light of FIG. 1;

FIG. 5 is a bottom view of the solar-powered area light of FIG. 1;

FIG. 6 is a perspective view of a solar-powered area light in accordance with another embodiment of the present invention;

FIG. 7 is a top view of the solar-powered area light of FIG. 6;

FIG. 8 is a side elevational view of the solar-powered area light of FIG. 6 having a mounting flange (shown in dashed lines) mounted to an enclosed structure (also shown in dashed lines) for lighting the interior of the structure;

FIG. 9 is a side elevational view of the solar-powered area light of FIG. 6; and,

FIG. 10 is a bottom view of the solar-powered area light of FIG. 6.

The dashed lines are shown for illustrative purposes only and form no part of the claimed design.
